Morris, Gorton & Saeger

Water Wheel

N° 13685.

Patented Oct. 16, 1855.

UNITED STATES PATENT OFFICE.

HIRAM MORRIS, ELIJAH K. GORTON, AND EDWARD SAEGER, OF CRAWFORD COUNTY, PENNSYLVANIA.

IMPACT WATER-WHEEL.

Specification forming part of Letters Patent No. 13,685, dated October 16, 1855.

To all whom it may concern:

Be it known that we, HIRAM MORRIS, ELIJAH K. GORTON, and EDWARD SAEGER, of the county of Crawford, State of Pennsylvania, have invented a new and Improved Water-Wheel; and we do hereby declare that the following is a full and exact description thereof, reference being had to the accompanying drawing, and to the letters of reference marked thereon.

To enable others to understand and make use of our invention, we will proceed to describe its construction and operation, reference being had to the drawings.

Figure 1 is a perspective drawing of our water-wheel, with all its parts adjusted in working order.

The wheel is constructed in two separate rims, the lower one shown at Fig. 2 and the upper one shown at Fig. 3. The wheel is supported on its shaft A, Fig. 1, by means of a spider B, Fig. 3, which is fastened by screw-bolts to the upper rim C, which spider is additionally supported by braces, one end hooking into eyes on the arm of the spider and the other end passing through eyes in a band on the shaft of the wheel, with a nut and screw, as seen at D D, Fig. 4. In the rims of the wheel are made circular grooves to receive the buckets, as seen at 1 2 3 4, Fig. 2. The grooves in both rims correspond with each other.

The buckets of the wheel are of any circle required by the size of the wheel and the number of buckets desired, the inside end turning in a shorter circle, as shown at E, Fig. 5. On the edges of the buckets a circular flange projects, as shown at F G, which fits into the circular grooves 1 2 3 4, Fig. 2, in the rims of the wheel. Passing through the buckets in a perpendicular direction is a slot H, Fig. 5. Through this slot a stud or bolt is passed, by which means the rims of the wheel are firmly bolted together, as seen at I I, Fig. 4, permitting, however, the buckets to slide in and out and by this means opening and closing the issues at any desired size. The buckets are kept in the position desired by means of a latch, as seen at 1 2 3 4 5 6 7, Fig. 1. This latch drops into any one of several catches at every bucket, as shown at 1, Fig. 1, there be-

ing a latch and corresponding catches at every bucket.

Fig. 6 is the wheel-bed, which is made convex, as shown at R R, Fig. 4. Around this bed is an iron rim A A, which is made true, so as to fit the inner circumference of the lower rim of the wheel to prevent the water being discharged between the bed and the wheel. In the center of this bed is our adjusting-box, a top view of which is shown in Fig. 6 and a side or sectional view at Fig. 4, where the wheel-bed is divided perpendicularly, in order better to show its convexity and the construction of the adjusting-box.

B, Fig. 6, is the core-plate of the box, in the center of which is a steel point, on which the shaft of the wheel runs, as seen at L, Fig. 4.

1 2 3 4, Fig. 6, are screw-bolts which pass through the core-plate B, the end resting on the bed-plate of the box D D, which is of iron, by which means the core-plate is lowered and raised, which lowers and raises the wheel. 5 6 7 8 are also screw-bolts which screw into the edges of the core-plate, the heads of these bolts resting against the inner rim of the bed-plate D D, by which means the wheel is adjusted laterally.

Fig. 7 is a packing-rim or decking to the wheel, which is placed over the wheel and is made concave on its upper surface. This decking is placed on the inside of the circular flume, Fig. 1, as seen at C, and rests upon its bottom so close to the wheel that when the wheel is adjusted to it by means of the adjusting-box it prevents the water being discharged around its upper surface. The studs or bolts which pass through the buckets to fasten the rims of the wheel together have a shoulder on each end, by which means the rims are firmly bolted together and leave the buckets room to move freely in the grooves of the rim.

This wheel has no bottom and is supported wholly by the spider B, Fig. 3, and the braces D D, Fig. 4. By this arrangement we get rid of much of the weight of the water, which would otherwise rest upon it.

What we claim as our invention, and desire to secure by Letters Patent, is—

1. The buckets, so constructed as to be adjusted and movable, to open and close the

issues as may be desired by means of the circular grooves in the rims of the wheel, and flanges on the buckets, and the studs and bolts passing through the buckets, and the fastening the buckets in any desired position by means of a latch and catch, in the manner described.

2. A circular concave packing-ring and

decking, with the adjusting-box constructed in the manner described.

HIRAM MORRIS.
